UNITED STATES PATENT OFFICE

2,491,730

MISSILE DROPPING DEVICE

Frederick H. Hagner, San Antonio, Tex.

Application May 2, 1946, Serial No. 666,802

1 Claim. (Cl. 33—206)

1

This invention relates to angle-determining devices, and has for one of its objects the production of a simple and efficient means for determining the angle of an object or other element against which it may abut relative to the true horizontal or vertical planes.

A further object of this invention is the production of an instrument comprising a simple and efficient means for releasing a missile from a supported position to drop said missile upon a recording element and thereby facilitate the measurement of the degree of deviation of the instrument from a true vertical or horizontal position at the time of dropping the missile.

Other objects and advantages of the present invention will appear throughout the following specification and claim.

In the drawings:

Figure 1 is a side elevational view of the angle-determining device;

Figure 2 is a side elevational view of the device taken at right-angles to Figure 1, the lower portion of the device being shown in vertical section;

Figure 3 is a transverse sectional view taken on line 3—3 of Figure 1;

Figure 4 is a side elevational view of the device in an inverted position;

Figure 5 is a vertical sectional view through the casing taken on line 5—5 of Figure 4, the mechanism being shown in edge elevation;

Figure 6 is a vertical sectional view through the casing of the device illustrating the opposite side of the mechanism from that shown in Figure 4;

Figure 7 is a horizontal sectional view taken on line 7—7 of Figure 4;

Figure 8 is an enlarged inverted vertical sectional view taken on line 8—8 of Figure 7;

Figure 9 is a fragmentary sectional view taken on line 9—9 of Figure 2.

By referring to the drawings, it will be seen that 15 designates a casing which is provided with a head portion 11 and a base portion 12. The head portion 11 is provided with a small bore aperture 13 which extends from the outer end of the head portion to the lower end of the depending neck 14 thereof, for the purpose hereinafter described.

A suitable frame 15 is hung from the head portion 11 and carries a transversely-extending operating shaft 16. This shaft 16 is provided with a notch, as at 17, for receiving a spring-actuated latch 18. The latch 18 holds the shaft 16 against rotation when the latch 18 engages the notch 17. An operating knob 19 is carried

2

by the shaft 16, and a contracting coil spring 20 is wound about the shank 21 of the knob 19. One end of the spring 20 is anchored to the shank 21 and the other end is anchored to the frame 15, as at 22. This spring 20 is adapted to accelerate the rotation of the knob 19 and the shaft 16 in a clockwise direction when the latch 18 is released from the notch 17.

A ball or missile-supporting finger 23 is fixed to the shaft 16 below the notch 17, as shown in Figure 8, and normally projects beyond the central longitudinal axis and the aperture 13 of the head portion 11, when the finger 23 is in a missile-supporting or engaging position. A bumper spring 24 is carried by the ball-engaging face of the finger 23 and a bumper spring 25 is carried by the reverse side of the finger 23 for providing a shock absorber to cushion the blow when the finger 23 is swung to a released position 20 in contact with the abutment 27 of the frame 15, such as is shown in dotted lines in Figure 8.

A latch release rod 28 is carried by the head portion 11 and engages the latch 18 to control the release of the latch 18. A trigger lever 29 is secured to the upper end of the rod 28 and a spring 30 is carried by the rod 28 to return the rod 29 to a lifted or returned position. The latch 18 is released from the shaft 16 to permit the spring 20 to rotate the shaft 16 by pressing down upon the trigger 29 and thereby moving the rod 28 and the outer end 31 of the latch 18 downwardly, the latch 18 being pivoted, as at 32.

The ball or missile 33 rests in a supported position upon the spring 24 of the finger 23 in the manner shown in Figure 8, and is moved to this position in the manner described in the following description. As the trigger 29 is depressed, the latch 18 is swung out of contact with the notch 17 and the spring 20 accelerates the rotation of the shaft 16 and the finger 23 is swung out of supporting contact with the ball or missile 33 at a relatively greater speed than the speed at which the missile drops, to drop the ball or missile 33 free from interference with the pull of gravity, to prevent deflection of the ball or missile 33 in its flight. The spring 20 rotates the shaft 16 to swing the finger 23 in contact with the abutment 27 to the dotted line position shown in Figure 8. This movement will instantaneously release the ball or missile 33, and permit the ball 33 to drop in the direction of the arrow and the dotted line position of the ball 33.

A recording means 34 is carried by the base portion 12, and this recording means 34 may be made 55 of any suitable material or combination of ma-

terials to cause a mark to be made upon the recording means when the missile 33 drops thereon after it is released by swinging the finger 23 to a releasing position shown in dotted lines in Figure 8. The recording means preferably comprises a flat plate having a plurality of concentric circles spaced in degrees from the center thereof constituting a target to facilitate measuring the position of a mark made thereon by a dropping ball relative to the center of the target. The base portion 12 is provided with channelled flanges 35 upon the inner or upper face of the base to slidably receive the edges of the recording plate 34 and anchor the same at both side edges and at the rear edge thereof. The plate 34 is provided with a forward lip 36 which is adapted to project through the aperture 37 in the casing 10 and contact the inner face of the outer sleeve 38 which is rotatably mounted upon the casing 10, as set forth in the following description. The recording means or plate 34 may be provided with a thin sheet of carbon or other paper upon its outer face to provide a contact mark upon the plate 34 when the ball 33 strikes the plate. It is not desired to limit the recording plate to any detail structure as many variations may be provided without departing from the spirit of the invention.

The base portion 11 is provided with an inset peripheral channel 39 beyond the edge of the recording plate 34 and this channel 39 communicates with apertures 40 which lead to the chamber 41 formed in the base portion 11. The chamber 41 is provided with a dished inner wall or bottom 42 which leads to an exit aperture 43. This aperture 43 leads to a cavity 44 at the bottom of the base portion 11. A projecting rim 45 is formed around the outer end of the exit aperture 43 to prevent the missiles from rolling back through the aperture 43 after being discharged therefrom. An inclined passageway 46 leads from the cavity 45 to the return tube 47 which extends longitudinally of the casing 10 and communicates with the inclined passageway 48 formed in the block 49 of the head portion 11. The passageway 48 leads from the tube 47 to the ball or missile seat 50 at the inner end of the aperture 13, as shown in Figure 8. A transverse check shaft 51 is carried adjacent the passageway 48 and is provided with a notch 52 which, when in line with the passageway 48 will permit a ball to pass to the seat 50, but the check shaft 51 will obstruct the passageway 48 when the shaft is in the position shown in Figure 8. The notched shaft 51 is connected to the shaft 16 by a link 53 which engages the arms 59 and 60, these arms being keyed to the respective shafts 16 and 51, to cause the shaft 51 to close the passageway 48 at its discharge end when the shaft 16 is in a latch-engaging and missile-supporting position shown in Figure 8.

The casing 10 is provided with an aperture 37 adjacent the base portion 12, which aperture 37 is so located as to facilitate the placing of the recording means or plate 34 in position and facilitate the removal of this plate. An outer sleeve 38 previously referred to fits snugly around the casing 10 and is held in engagement therewith by means of a screw 61 which passes through a slot 62 in the sleeve 38 to limit the rotation thereof. The sleeve 38 is provided with an aperture 63 in the same horizontal plane with the aperture 37, and this aperture 63 is adapted to be brought into registration with the aperture 37 by rotating the sleeve 38 upon the casing 10 in a clockwise direction when the device is in a position shown in

Figure 1. Then by reversing this turning movement the apertures may be brought out of registration, thereby closing the aperture 37.

The casing 10 is provided with an aperture 64 located in a position to permit access to the operating knob 19 (see Figure 4), and the sleeve 38 is provided with a registering aperture 65 which is adapted to be brought into an overlying or registering position with the aperture 64 to permit an operator to actuate the knob 19. By means of this structure, the apertures 64 and 37 may be opened and closed merely by rotating the sleeve 38 upon the casing 10 to a proper position. It should be understood that the casing 10 and the sleeve 38 may be made of any suitable material preferably of metal, but the parts may be made of transparent plastic if desired, without departing from the spirit of the invention.

The lower end of the casing 10 is preferably closed by means of a closure means 66 of any suitable type.

The device may be placed so as to have the closure 66 rest upon an approximately horizontal support to determine the angle of deviation from the normal horizontal position, or the side of the device may be placed against a substantially vertical surface to measure the angle of deviation. The present device may be used in various ways to determine degree of tilt or angle of deviation from a normally level or upright position and may be used with many types of apparatus without departing from the spirit of the invention.

The purpose of the aperture 13 is to permit a slender rod to be inserted therethrough when the finger 33 is in the open position or dotted-line position shown in Figure 8, such rod when passing through the aperture 13 being used to determine the exact center on the base portion 12 when the position of such center is found necessary or desirable to locate the center of the base portion 12.

When the device is in a ball-dropping position, the casing 10 is placed in an upright position, such as is shown in Figures 1 and 2, and the sleeve 38 is rotated to align the apertures 64 and 65 so that access may be had to the knob 19. After the ball is dropped, the sleeve 38 is rotated to move the aperture 65 out of alignment with the aperture 64. After the desired recording has been made upon the recording means 34, the balls or missiles are dropped into the cavity 44 and the casing is then inverted to cause the missiles or balls to roll down through the tube 47 and passageway 48, one ball passing to a proper position upon the ball-receiving means or seat 50. The notched shaft 51 will permit only one ball to be fed at a time to the seat. After one ball has been fed to the seat position, the shaft 16 is rotated to swing the finger 23 to a ball-gripping position and the casing is then again inverted to bring the parts into the position shown in Figures 1, 2 and 8, or to a ball-dropping position.

Having described the invention, what is claimed is:

A missile-dropping device comprising a support having a missile seat, a spherical missile having diametrically located extreme points at its upper and lower ends in line with its vertical axis, the upper extreme point of said missile fitting in said seat, a missile-supporting finger pivotally supported upon said support laterally of said seat, latching means for holding said

finger in a missile-engaging position, said finger contacting only the lower extreme point of said missile, means for releasing said latching means, means for automatically swinging said finger away from said missile when said finger is released to drop the missile free from interference with the pull of gravity at the time of the release of said missile, and a missile-contacting spring carried by said finger and yieldably supporting said missile in engagement with said seat.
